UNITED STATES PATENT OFFICE.

CLARANCE E. SAFFORD, OF LANCASTER, NEW YORK.

STEAM-GENERATOR.

SPECIFICATION forming part of Letters Patent No. 309,651, dated December 23, 1884.

Application filed April 19, 1884. (No model.)

To all whom it may concern:

Be it known that I, CLARANCE E. SAFFORD, of Lancaster, in the county of Erie and State of New York, have invented a new and useful Improvement in Steam-Generators, of which the following is a specification.

This invention relates to an improvement in that class of steam-generators which are composed of a series of similar cast sections 1c suitably connected at their upper and lower ends to establish communication between the steam and water spaces of the respective sections.

The object of my invention is to construct the sections of the boiler or steam-generator in such manner that the heat generated by the burning fuel is thoroughly utilized, and so that the generator shall be simple in construction and capable of being easily cleaned when required.

My invention consists of the improvements in the construction of the boiler which will be hereinafter fully set forth, and pointed out in the claims.

25 In the accompanying drawings, consisting of two sheets, Figure 1 is an end elevation of the steam-generator with a portion of the inclosing-casing broken away. Fig. 2 is a longitudinal section of the generator. Fig. 3 is a 30 horizontal section in line xx , Fig. 1. Fig. 4 is a horizontal section in line yy , Fig. 2. Fig. 5 is a vertical cross-section in line zz , Fig. 2. Fig. 6 is a vertical longitudinal section in line ww , Fig. 4. Fig. 7 is a horizontal section, on 35 an enlarged scale, of the pipe-connections at the upper ends of the sections. Fig. 8 is a horizontal section, on an enlarged scale, of the cleaning-tubes. Fig. 9 is a perspective view of one of the sections.

40 Like letters of reference refer to like parts in the several figures.

A represents the brick-work or other casing inclosing the steam-generator, and A' the grate arranged in the lower portion thereof above the ash-pit A².

a represents the fire-door; a', the ash-pit door, and a² and a³ flues leading, respectively, from the upper and lower portions of the casing A to the chimney.

45 B represents the upright sections of the generator, arranged transversely in two rows on opposite sides of the grate between the front

section, C, and the rear section, D, the two latter sections extending entirely across the generator, as represented in Fig. 4.

55

Each of the sections B consists of a hollow body, B', overhanging the grate, and a leg or downwardly-extending portion, B², resting on the masonry or other support on one side of the grate. The tops of the several sections B 60 fit closely against each other when the sections are in place, so as to form a tight top. The inner faces, b', and the sides b² of the sections recede from the edges of the top b, forming flame-spaces e between the inner faces, b', and 65 flame-spaces e' between the sides b². The inner faces, b', and sides b² connect with the top by easy curves, as shown.

f are upright hollow extensions or enlargements formed on the sides b² of the body portions B' of the sections, and communicating with the hollow interior space of the same.

f' are upright elongated flame-passages extending through the bodies B' of the sections on the outer sides of the enlargements f.

75

f² are similar hollow enlargements formed along the inner edges of the legs B², and extending upwardly along the body portions B'. The enlargements f² are made so large that their faces rest against each other when the sections are in place, while the enlargements f are smaller, leaving flame-spaces f³ between their faces, as represented in Fig. 4. The enlargements f' f² do not extend to the top b of the section, but leave flame-spaces f¹ between 85 their upper ends and the top.

g represents similar upright hollow enlargements formed along the outer edges of each section, extending from the top downwardly, and terminating above the lower ends of the legs B', so as to leave passages g' below the lower ends of the enlargements.

h represents upright flame-passages formed through the body B' of each section between the enlargements f² and g.

95

I represents a space or passage formed between the sides and rear walls of the casing A and the generator, and communicating with the chimney by the flues a² a³.

J represents a laterally-projecting hollow lug or ear formed on the upper portion of each section; and j represents short pipes, whereby the lugs J of two adjoining sections are connected. The pipes j are each provided with

screw-threads at opposite ends, and screwed into correspondingly-threaded openings in the lugs *J*, and secured by jam-nuts *j'*, as represented in Fig. 7. The pipes *j* establish communication between the steam-spaces of the several sections. Similar pipes, *k*, are employed for establishing communication between the water-spaces at the lower ends of the several sections.

10 *L* represents an opening formed in the lower portion of the front section, *C*, in line with the fire-door *a*, for giving access to the grate. The front and rear sections, *C* and *D*, are provided on their inner sides with hollow enlargements *f f' g*, corresponding with the enlargements of the section *B*.

15 *m* are semicircular recesses formed in the faces of the outer enlargements, *g*, of the several sections near their upper ends and above the upper ends of the enlargements *f f'*.

20 *n* are tubes resting with their inner ends in the adjoining recesses *m* of two sections, and extending outwardly through openings in the casing *A*, their outer ends being closed by removable caps or covers *n'*, as represented in Figs. 3 and 8.

25 The enlargements *f f' g* and the passages *f' h* divide the interior space of each section, so as to present their bodies of water to the action of the flame and hot gases, thereby increasing the heating-surface and enabling the apparatus to generate steam quickly and economically.

30 The enlargements *f' g* form the outer walls of the combustion-chamber in which the flame and hot gases rise from the fuel on the grate to the top of the generator.

35 The spaces between the enlargements *f' g* form diving or return flues, by which the hot gases descend from the top of the generator to the lower openings, *g'*, through which the gases escape into the passage *I*, surrounding the sides and rear end of the generator.

40 When it is desired to clear the sections from ashes, &c., which may adhere to the same, the caps *n'* are removed and steam-jets are introduced through the tubes *n*, which jets can be readily directed against the innermost por-

tions of the sections, whereby the latter are quickly freed from all deposits adhering to their outer surfaces.

I claim as my invention—

1. In a steam-generator, a section, *B*, composed of an overhanging body, *B'*, a downwardly-extending leg, *B''*, and upright enlargements *f f' g*, with passages *f' h* above the enlargements *f' g*, and intermediate flame-passages, *f' h*, extending through the sections, substantially as set forth. 55

2. In a steam-generator, a section, *B*, composed of an overhanging body, *B'*, downwardly-extending leg, *B''*, upright enlargements *f f' g*, and intermediate flame-passages, *f' h*, substantially as set forth. 60

3. The combination, with the intermediate sections, *B*, provided with upright enlargements *f' g*, front and rear sections, *C* and *D*, constructed on their inner sides with similar enlargements, *f' g*, hollow lugs *J*, formed on the several sections, and connecting-pipes *j* and *k*, substantially as set forth. 70

4. The combination, with the sections *B*, having their tops *b* constructed to rest closely against each other, and having receding inner faces, *b'*, and sides *b''*, forming flame-passages, of the projecting enlargements *f' g*, formed on the sides of the sections, front and rear sections, *C* and *D*, and an inclosing-case, *A*, substantially as set forth. 75

5. In a steam-generator, a section, *B*, provided along its outer edge with an enlargement, *g*, having a recess, *m*, near its upper end, substantially as set forth. 80

6. The combination, with the casing *A* and the sections *B*, having enlargements *g*, provided with recesses *m*, of the tubes *n*, extending from said recesses outwardly through the casing, and provided with removable covers, substantially as set forth. 85

Witness my hand this 14th day of April, 1884.

CLARANCE E. SAFFORD.
